UNITED STATES PATENT OFFICE.

THOMAS E. McCANN, OF MILLER, KANSAS.

DEVICE FOR DELIVERING TRAIN-ORDERS.

No. 914,158.

Specification of Letters Patent. Patented March 2, 1909.

Application filed November 6, 1908. Serial No. 461,859.

To all whom it may concern:

Be it known that I, THOMAS E. McCANN, a citizen of the United States, residing at Miller, in the county of Lyon and State of Kansas, have invented certain new and useful Improvements in Devices for Delivering Train-Orders, of which the following is a specification.

My invention relates to improvements in devices for delivering orders to moving trains and its principal object or most important feature is its simplicity of construction.

It consists of nothing more than a handle member having mounted at one extremity, a semi-hoop to which is attached the message or article to be delivered to the train. This device avoids the necessity of trains stopping thereby saving time and indirectly labor and train wear as is the result of trains stopping too often particularly express trains.

My invention is fully disclosed in the following specification of which the accompanying drawings form a part, in which the separate parts of my improvement are designated by suitable reference characters in each of the views and in which—

Figure 1 is a plan view of the device showing the message in its delivering position. Fig. 2 is an enlarged detail view of one of the fork extremities of the cord retaining device. Fig. 3 is a modified form. Fig. 4 is an enlarged detail view of one of the spring members which retain the cord.

Let the numeral 5 designate a handle having mounted on its upper extremity an overlapping band or U-shaped fastening device 6. This fastening device is secured to the handle member 5 by means of screws or rivets 7 being passed through openings formed in both the handle 5 and the member 6. Also mounted on the upper extremity of the handle 5 and passing between the said handle and the member 6, is a semi-hoop shaped member 8 preferably made of wire or some other yielding material which will give when a slight pressure is applied thereto. Each extremity of this member 8 is forked by having mounted thereon the parts 9. These parts 9 consist of a flat portion 10 which are placed adjacent the inner surface of the member 8 and are fastened thereto by means of rivets 12 being passed through apertures formed in both members 8 and 10. These parts 9 have also an offset portion 10^a which forms the fork construction heretofore described.

Located on the member 8 on the opposite sides of the handle member are spring devices 13. These spring devices are composed of a circular portion 14 which surrounds the member 8 and an elliptical portion 15. The said elliptical portion terminating at one extremity into outwardly flared lips 16 and at the other extremity into a neck portion 17. The neck portion 17 connects the members 14 and 15. These spring members are held in a given position on the member 8 by means of fastening devices 18 which are passed through openings formed in the neck portion 17. It must be understood that the elliptical portion 15 is open or adapted to be opened at the top for the reception of a cord 19 which carries the message 20. The cord 19 is passed around each fork extremity of the member 8 or around the offset portion 10^a of the member 9 and is then passed between the lips 16 into the elliptical portion 15 of the spring member 13, one spring member as before stated being located on each side of the upper extremity of the handle 5.

In carrying out the invention, the trainman while on a moving train inserts his arm through the loop formed by the cord. By doing this the tension which is applied to the cord from the arm by means of the train moving causes the member 8 to yield and allows the cord with the message to slip over the fork extremities 9 and be pulled out of engagement with the spring members 13. In this way, the message is delivered to a moving train without any delay or trouble.

In the modified form, I substitute for the members 9 spring members 21 composed of a flat portion 22 which is connected to the member 8^a by means of rivets 23. The other extremity of the spring member 21 is provided with an eye or loop 24 which is threaded with one extremity of a cord 25, the other extremity of the cord being connected in a like manner to the corresponding spring members 21. The handle member 5^a is provided with eye screws 26 through which is longitudinally movable an auxiliary handle 27, the upper extremity of said handle being provided with an eye 28 through which passes the cord 25. Just above the upper eye screw 26 is mounted an eye screw 29 which acts as a guide for the cord 25.

The operation of this modified form is as follows: The trainman in the same manner as described above, places his arm through

the cord which carries the message (not shown in Fig. 3) and detaches the said message and cord the same way as heretofore described, except that the members 21 yield by means of the operator on the ground pulling downwardly on the handle 27, thereby avoiding the necessity of the member 8 yielding as described in Fig. 2. This also prevents any possible chance of the message and cord not being detached. Furthermore the spring members 21 bear against the semi-loop and keep what would be the fork construction, normally closed thus preventing the message and cord from becoming accidentally detached. This modified form is merely to illustrate that the construction may be varied without departing from the spirit of the invention.

It will be observed that by making the member 8 in the form of an open half or semi-hoop that the order can be easily be placed between the opening provided between the free ends of the member and permit the trainman to take the order in his hand or quickly insert his arm on the opening between the semi-hoop and detach the order with ease and the open semi-hoop construction is one of the most important features of my invention as it enables the easy and quick detachment of the order.

What I claim is:

1. A device for delivering train orders comprising a handle, a yielding device mounted on the handle and fastening devices mounted on the yielding device for carrying the order said yielding device con-

sisting of a fork or open semi-hoop between which the order is placed.

2. In a device for delivering train orders comprising a handle, a yielding device mounted on the handle having upper fork extremities, spring members mounted on the yielding device, and a cord held by the fork extremities and the spring members, said cord having attached thereto the order.

3. A device for delivering orders to moving trains comprising a handle and a yielding device mounted on the upper extremity of the handle which carries the order, said yielding device consisting of an open fork, devices carried by the fork for holding and guiding the cord to which the train order is connected and permitting the quick and easy removal of the cord with the train order from the fork.

4. A device for delivering orders to moving trains comprising a handle member, a semi-loop yielding device mounted on the handle member, spring means mounted on the yielding device on opposite sides of the handle member, and offset devices mounted on the extremities of the yielding member, the said offset devices and spring means constituting a retaining means for the order, substantially as described.

In testimony whereof I affix my signature, in presence of two witnesses.

THOMAS E. McCANN.
